UNITED STATES PATENT OFFICE.

ELMER T. McCARTHY, OF EVANSTON, ILLINOIS, ASSIGNOR TO D. H. SKEEN & COMPANY, OF CHICAGO, ILLINOIS, A COPARTNERSHIP COMPOSED OF DAWSON H. SKEEN, OF CHICAGO, ILLINOIS, AND ELMER T. McCARTHY, OF EVANSTON, ILLINOIS.

LIQUID COLUMN FOR PRODUCING STATIC STRESSES.

Application filed February 9, 1925. Serial No. 7,782.

This invention relates to liquid columns for producing static stresses, particularly designed and adapted for producing differential pressures and relates particularly to 5 the production of such static stress by means of mercury columns.

A particular application for which a static column of my invention is especially adapted is for use in connection with automatic 10 valve control means adapted for regulating the flow of fluid under pressure in order to produce differential pressures.

Among specific applications for which my improved static column is especially designed and adapted, are the following:—

On pressure regulators for steam driven feed pumps for boilers;

On pressure regulators for boiler feed pumps driven by motive force other than 20 steam from the boiler to which the water is fed.

On constant pressure regulators or reducing valves; and

On back pressure regulators or relief 25 valves.

Principal objects of the invention are:—

To prevent loss and leakage of mercury in static mercury columns;

To provide automatic fluid pressure regulators of the general type specified, so constructed and arranged that the static column applied to the motive means for operating the valve control means may be installed at any elevation relative to the motive means; 35 and

To provide means, both manually operated and automatic means, for varying the effective height of the static column to compensate for variations in pressure due to 40 friction or other causes.

Broadly stated, a static column of mercury or other liquid embodying my invention comprises upper and lower pots, a tube which connects said pots and which communicates with said pots, respectively, substantially at the designed minimum levels therein of the mercury or other liquid forming said static column, each of said pots being proportioned to hold somewhat more than all of the mercury or other liquid forming such static column, and a pipe adapted for connecting one of said pots above the designed maximum level therein of the

liquid forming said static column, with a closed expandable chamber forming motive 55 means, said expandable chamber, pipe and pot containing water or other liquid of less specific gravity than the mercury or other liquid forming said static column, whereby any leakage which may occur in said pipe 60 and its connections will be of liquid other than that which forms said static column—specifically mercury.

More specifically, a static column embodying my invention comprises a mercury leg 65 consisting of upper and lower pots, a tube which connects said pots and which communicates with said pots, respectively, substantially at the designed minimum levels therein of the mercury forming said static 70 column, each of said pots being proportioned to hold somewhat more than all of the mercury in said column, and a water leg which communicates with the upper pot of the mercury leg above the designed maximum 75 mercury level therein adapted for connecting said upper pot with an expandable chamber providing motive means for the movable control member of a fluid pressure regulating valve, and a pipe which communicated with the lower pot of the mercury column above the designed maximum mercury level therein adapted for connecting said pot with a source of supply of fluid under pressure. Obviously, with this construction, the mercury is confined to the mercury pots and the tube which connect said pots, thus reducing the number of joints at which leakage of mercury can occur, reducing and practically preventing loss of 80 mercury.

With the described construction, also, it is obvious that the static column may be installed at any desired elevation relative to the expandable chamber forming the motive 85 means.

As the invention relates to manually operated means for varying the effective height of the static column, I effect the object of the invention by means of a by-pass 100 which connects the water leg of the static column with the pressure pipe which communicates with the lower mercury pot, a valve—preferably a needle valve—which controls said by-pass, and a vent valve applied to said water leg, conveniently to the 105

section of said by-pass between the control valve therein and the water leg of the static column

Any desired variation may be provided for by properly proportioning the height of the pots forming the mercury column, and the use of a corresponding quantity of mercury.

The desirability of thus varying the effective height of the mercury column and thereby the static pressure produced is to compensate for varying pressure losses due to friction in the system, to which said static column is applied, at varying rates of flow therein.

As my invention relates to means for automatically producing variations in the effective height of the static mercury column, I attain the objects of the invention by forming the tube which connects the upper and lower mercury pots of the mercury leg of said static column with an enlarged lower portion which communicates with the lower mercury pot adjacent to its lower end and the height of which corresponds to any contemplated variation in the height of the mercury column to compensate for friction losses; means for forming passageways within the enlarged lower portion of said tube which extend substantially from end to end thereof and are of such small bore that water or other liquid of less specific gravity than mercury, will not rise through the mercury contained in said tubes and the aggregate cross sectional area of which is relatively much less than that of the upper pot, the relation being such that variations in the level of the mercury in the upper pot will produce much greater variations in the level of the lower end of said static column, thereby producing corresponding variations in the effective height of said static column. In accordance with my invention, automatic control of the effective height of the mercury column contemplates that the lower end of the mercury column shall at all times be within and above the lower end of the enlarged lower portion of the tube connecting the upper and lower pots of the mercury leg.

My invention also comprises the various other features, combinations of features and details of construction hereinafter described and claimed.

In the accompanying drawings, in which my invention is fully illustrated and in which I have shown different applications of my improved static column,

Figure 1 is a vertical sectional view of a static column embodying my invention and improvements shown as applied in use to a pressure regulator for a steam driven feed water pump for boilers.

Figure 2 is a view substantially similar to Fig. 1, showing a static column of my in-

vention comprising means, both manually operated and automatic, for varying the effective height of the static column.

Figure 3 is an enlarged longitudinal sectional view in a plane ninety degrees to the line 3-3 of Fig. 2.

Figure 4 is a transverse sectional view on the line 4-4 of Fig. 3.

Figures 5, 6 and 7 are views similar to Fig. 4, illustrating modifications.

Figure 8 is a view substantially similar to Fig. 1, showing my improved static column applied in use to a feed water pump for boilers driven by power other than steam from the boiler to which the water is fed.

Figure 9 is a view substantially similar to Fig. 1 showing my improved static column applied in use to a regulator for producing a constant pressure reduction.

Figure 10 is a fragmentary view illustrating a modification; and

Figure 11 is a diagrammatic view showing a fluid pressure regulator comprising a static column like that shown in Fig. 1, applied in use to the feed water pump for supplying water to a boiler.

In the accompanying drawings I have, for purposes of clear and definite illustration, shown several different applications of a static liquid column—specifically a mercury column—embodying my invention and improvements, which will be separately described.

Referring now particularly to Figs. 1 and 11 of the drawings, in which I have shown my improved static column as applied to a differential pressure regulator for steam driven feed pumps for boilers, A designates as a whole, a control valve of the balanced type, comprising a casing 1, provided with steam admission and discharge openings 2 and 3 adapted to be connected into the steam line 4 for supplying steam from a steam boiler 5 to a steam driven pump 6 (Fig. 11), for supplying feed water to said boiler.

My invention contemplates the use of any suitable or desired form of control valve, of which different kinds suitable for the purpose may be purchased commercially, and said valve need not, therefore, be described in detail.

The valve casing 1 forms part of a pressure regulator which also comprises a diaphragm casing 7 which communicates with said valve casing 1 by means of a trunk 8, said diaphragm casing being divided by a diaphragm 9 into separate compartments 10 and 11, whereby the surface of the diaphragm 9, exposed in the compartment 10 of the diaphragm casing, will be subjected substantially to the full steam pressure of the boiler. In the operation of the device, the trunk 8 will become filled with water of condensation and, in practice, said trunk will be made of such length that the water in the

trunk 8 adjacent to the diaphragm 9 will be of such low temperature that said diaphragm will not be injuriously affected thereby.

- 5 The valve plug or piston 12 is connected by a rod or stem 13 with the diaphragm 9, whereby flexure of said diaphragm by excess pressure on one side or the other thereof, will operate to impart movement to said 10 valve plug or piston to open or close the same, as the case may be. As shown, the relation is such that flexure of the diaphragm 9 due to an unbalanced excess steam pressure in the compartment 10 of the diaphragm casing, will impart movement to the movable valve member, specifically the plug or piston 12, to open the valve, while flexure of said diaphragm due to an unbalanced excess pressure in the compartment 11 20 of said diaphragm casing will impart movement to said movable valve member to close the same. In the type of pressure regulator shown, the compartment 11 of the diaphragm casing has pipe connection with the 25 pump discharge line through a static liquid column. As shown, said liquid column, which embodies my invention and improvements, comprises a mercury leg and a water leg, which communicate with each other at their upper ends. The mercury leg of said 30 static column comprises closed upper and lower pots 14 and 15 and a tube 16, which connects said pots, and which communicates with said pots, respectively, adjacent to 35 their lower ends and which define the minimum mercury levels therein, each of said pots being proportioned to hold somewhat more than all of the mercury contained in the apparatus.
- 40 The water leg of said static column consists of a pipe 17, one end of which communicates directly with the compartment 11 of the diaphragm casing, and the opposite end of which communicates with the upper pot 14 of the mercury leg above the 45 designed maximum mercury level therein.

The discharge opening from the pump 6 is connected with the boiler 5 by a pipe 18, Fig. 11, with which the lower pot 15 of the 50 mercury leg is connected above the designed maximum mercury level therein, by a pipe 19.

With the described construction it is obvious that when the valve A is fully open, a maximum quantity of steam will be delivered to the pump and said pump will be driven at maximum speed, the relation being such that when the pump is running at approximately full speed, the pressure in the feed water pipe 18 will be sufficient to overcome the water friction in the pipe, raise the column of water from the pump to the boiler inlet, and provide a sufficient excess of feed water pressure over boiler pressure to insure the delivery of a contemplated

quantity of feed water to the boiler. So long as the valve A is fully open, or approximately so, the pump will continue to run at full speed, but whenever the feed water pressure becomes sufficient to overcome the 70 combined steam pressure on the diaphragm in the compartment 10 of the diaphragm casing and the effective head of the mercury column, water will be forced into the lower pot 15 through the pipe 19, which will, in 75 turn, force mercury from the lower pot 15 into the tube 16 and from said tube into the upper pot 14, forcing water from said upper pot into the water leg 17, and from the water leg 17 into the compartment 11 of the 80 diaphragm casing, thus flexing the diaphragm 9 in a direction to close the valve A, reducing the speed of the boiler feed pump and the feed water pressure, and maintaining, at all times, a constant excess 85 of feed water pressure over steam pressure at the pump, corresponding to the effective head of the mercury column, which may be figured at approximately one pound for each two inches in height of said mercury 90 column.

It is found in practice that due to the high pressure in the pipe 17 and its connections, it is difficult to prevent leakage of water at the joints therein.

With a static column constructed as described, it is obvious that any leakage which may occur in said pipe 17, will at once be replaced from the pot 14, thus maintaining said water leg and the compartment 11 full 100 of water at all times. Also, in case the leakage continues until a quantity of water substantially equal in volume to the quantity of mercury in the lower pot 15 above the lower end of the tube 16, has escaped, the mercury 105 in said lower pot 15 will be forced upwards through the tube 16, thus permitting water contained in said pot to enter the open lower end of said tube 16 which, due to its less specific gravity, will rise through the mercury in said tube to the pot 14, thus at all 110 times compensating for any water leakage in the water leg. Also, by so proportioning the size of the pots 14 and 15 that each will contain somewhat more than all of the mercury in the apparatus, it is obvious that no mercury will be delivered from the upper 115 pot 14 into the water leg 17, or the compartment 11 of the diaphragm casing 7, thus effectually preventing mercury from passing 120 from the upper pot 14 into the water leg, reducing the quantity of mercury in the mercury leg and preventing deterioration of the pipe 17 and its fittings by the action of the mercury.

With the desired construction, also, it is obvious that said column may be installed in any desired position relative to the diaphragm casing 7, a usual arrangement being one in which the lower mercury pot will be 130

substantially at the level of said diaphragm casing, thus obviating the work and expense of constructing a pit or well for said mercury column as is necessary, for example, with static columns of the type shown in U. S. Letters Patent No. 1,452,223, dated October 12, 1921.

When the pump is shut off, the weight of the mercury column acting on the diaphragm 9, will operate to maintain the valve 10 A fully open.

My invention, also, contemplates means for varying the effective head of the static column, to compensate for variations in pressure due to friction or other causes, both manually operated and automatic means being provided for this purpose. Such means are shown in Figs. 2 to 7, inclusive, of the drawings and will now be described.

20 To effect the object of the invention as it relates to providing manually operated means for varying the effective height of the static column, I effect said object by means of a by-pass which connects the water leg 25 17 of the static column with the pipe 19 which connects the lower pot 15 with the feed water pump 6, said pipe being controlled by a valve—preferably a needle valve—and said water leg being provided 30 with a vent valve, which may conveniently be installed in the by-pass between the control valve therein and the water leg of the static column. Said vent valve, also, will preferably be a needle valve.

35 With the construction specified, it is obvious that the effective height of the mercury column may be increased by venting the water leg to permit the discharge of water therefrom, whereupon the water pressure in 40 the pipe 19 and the lower mercury pot will operate to force mercury from said lower pot upwards in the tube 16 into the upper pot 14, thus increasing the distance between the mercury levels in the two pots and correspondingly increasing the effective height 45 of the mercury column, in the manner desired; the rise of the mercury level in the upper pot operating to force water therefrom into the water leg 17 to replace that 50 discharged from said water leg.

On the other hand, when it is desired to reduce the effective height of the mercury column, this may be effected by opening the valve which controls the by-pass connecting 55 the lower mercury pot with the water leg 17, thus establishing communication between said lower pot and said water leg, balancing the water pressure on opposite ends of the mercury column and permitting mercury to 60 flow by gravity from the upper mercury pot into the lower mercury pot, water to replace the mercury which passes out of said upper pot being replaced by water which passes from the pipe 19 into the pipe 17 thus forcing 65 water from said pipe 17 into said upper

pot. Thus the mercury level in said upper pot will be lowered and the mercury level in the lower pot raised, correspondingly reducing the effective height of said mercury column.

70 This modification is shown in Fig. 2 of the drawings in which 7' designates the diaphragm casing; 8' the trunk which connects said diaphragm casing with the casing of the control valve in the steam line; 14' and 15' the upper and lower mercury pots; 16' the tube connecting said pots; 17' the water leg connecting the upper mercury pot with the diaphragm casing; 19' the pipe connecting the lower mercury pot with the feed 75 water pipe; 20 the by-pass connecting the pipe 19' with the water leg 17'; 21 a needle valve which controls said by-pass; and 22 a valve in said by-pass between the needle 80 valve 21 and the water leg adapted for discharging water from the water leg.

85 With the described construction it is obvious that, within defined limits, variations in the effective head of the mercury column may be obtained by properly proportioning the depth of the pots 14' and 15' and the quantity of mercury contained therein.

90 The foregoing description of means for varying the effective height of the mercury column manually, assumes that the lower mercury pot shall be partially filled with mercury outside of the tube 16 and to a level above the lower end thereof, and attention is called to the fact that changes in the mercury levels in the upper and lower pots, to 95 produce changes in the effective height of the mercury column are in opposite directions—rising in one pot and falling in the other. Under certain conditions, however, variations in the effective height of the mercury column are produced by differential changes in the levels of the upper and lower ends of the mercury leg in the same direction, as hereinafter explained.

100 As the invention relates to providing automatic means for varying the effective height of the static column, I effect the object of the invention in the following manner, as shown in Figs. 2 to 7 of the drawings:

105 The tube 16' which connects the upper and lower mercury pots, comprises an enlarged lower portion 23, the length of which corresponds to any contemplated or desired variation in the effective height of the mercury column to compensate for varying pressure losses due to friction in the steam and feed water lines, or other causes.

110 The enlarged lower portion 23 of said tube 16' is provided with passageways 24 which extend entirely through the same from end to end, said passageways being of such small 115 size that water or other liquid of less specific gravity than mercury will not rise through the mercury contained in said passageways and the aggregate cross sectional area of 120

said passageways being relatively much less than that of the upper pot, the relation being such that variations in the level of the mercury in the upper pot caused by movement of the diaphragm 9 will produce much greater variations in the level of the lower end of said static column, thereby producing corresponding variations in the effective height of said static column in a direction to produce a greater effective height of the column and consequently greater differential pressure, when the diaphragm moves in a direction to increase the valve opening and thereby increases the flow of steam and water in the system controlled by the pump regulator, and vice versa. Also, the cross sectional area of said passageways may be made to vary at different levels so that the differential pressure will vary according to any desired law at different rates of flow of the fluids controlled by the valve A.

The passageways 24 may be formed in any desired manner, as for example:—

1.—By round tubes 25 which are packed in the enlarged lower portion 23 of the tube 16', said passageways 24 being formed in part by the bores of said tubes and in part by the spaces between adjacent tubes, as shown in Fig. 4;

2.—By square tubes 26 which are packed into the enlarged lower portion 23 of the tube 16' so as to entirely fill the same, said passageways being formed by the bores of said tubes, as shown in Fig. 5;

3.—By tubes 27 of any desired shape, as shown round tubes, which are secured in the enlarged lower portion 23 of the tube 16' by cement or the like, which entirely closes the spaces between adjacent tubes, the passageways 24 being formed by the bores of said tubes, as shown in Fig. 6 of the drawings; or

4.—By rods 28, preferably round rods, which are packed into the enlarged lower portion 23 of the tube 16' so as to fill the same, the passageways 24 being formed entirely by the spaces defined by said rods, as shown in Fig. 7.

In accordance with my invention automatic control of the effective height of the mercury column contemplates that the lower end of said column shall at all times be within and between the ends of the passageways 24, the length of which correspond to a desired maximum variation in the effective height of the mercury leg, the length of said passageways varying in any given case with the ratio of the aggregate cross sectional areas of the passageways 24 and the upper mercury pot. A desired ratio in most application of the aggregate cross sectional areas of said passageways 24 to that of the upper mercury pot is approximately 1 to 10. With this relation it is obvious that a variation of one inch in the mercury level in the

upper pot will produce a variation of ten inches in the level of the lower end of the mercury column in the same direction, or of nine inches in the effective height of said mercury column.

Automatic control of the effective height of the mercury leg is based upon the discovery that with passageways 24 of sufficiently small size—say not exceeding the area of the bore of a tube $\frac{1}{16}$ of an inch in inside diameter—water contained in the lower end of the enlarged lower portion 23 of the tube 16' will not rise through mercury contained in said tubes above the water therein.

The passageways 24 are formed in such manner that their upper ends will be in open communication with the tube 16' and their lower ends with the lower pot 15', so that liquid will be free to enter said passageways—either water from the lower pot or mercury from the upper pot.

Regulating apparatus embodying my invention designed for use under conditions where there is a considerable pressure loss due to friction preferably embodies both manually controlled and automatic means for varying the effective height of the static column, the manual control being provided primarily for the purpose of initially adjusting the level of the lower end of the mercury column and the automatic control to compensate for variations in pressure due to varying friction losses or other causes.

My invention, however, also contemplates the separate use of said manually operated and automatic control means, if desired.

Pressure regulating apparatus embodying a static mercury column embodying my invention and improvements and equipped with my improved means for automatically varying the effective height of the mercury column to compensate for variations in pressure due to varying friction losses—either separately or in association with manually operated means for varying the effective height of the mercury column—presents conditions hereinbefore referred to, in which variations in the effective height of the mercury column are produced by differential changes in the levels of the upper and lower ends of the mercury column in the same direction.

Attention is called to the fact, also, that while the discharge of water from the water leg 17' will always raise the mercury level in the upper pot, it will produce a proportionate change in the mercury level in the lower pot, but in the opposite direction, where said lower pot is partially filled with mercury outside of the tube 16', thus increasing the effective height of the mercury column; or a differential variation in the level of the lower end of the mercury column in the same direction, if the lower end

of said mercury column is within and between the ends of the passageways 24 in the enlarged lower portion 23 of said tube 16', thus decreasing the effective height of the mercury column. Conversely forcing water into the water leg, will reduce the effective height of the mercury column, if the lower pot contains mercury outside of and above the lower end of the tube 16', or will increase the effective height of the mercury column, if the level of its lower end is within and above the lower end of said passageways 24.

Attention is called to the further fact, also, that in a pressure regulator embodying my improved static column, constructed and arranged for automatically varying the effective height of the mercury column to compensate for variations in pressure due to varying friction, as shown in Figs. 2 to 7 of the drawings, leakage in the water leg 17' will not be replaced automatically, for the reason, as previously explained, that the passageways 24 in the enlarged lower portion 23 of the tube 16' are of such small size that water will not rise through mercury contained therein. Obviously, therefore, to replace leakage in the water leg, it will be necessary to provide means for forcing water into said water leg, as the by-pass 20 and the valve 21 which controls said by-pass.

In Fig. 8 of the drawings I have shown my improved static column as applied in use to a feed water pump for boilers, driven by motive force other than steam from the boiler to which the water is fed, usually an electrically driven pump.

In this application of my improved static column, the regulator which controls the delivery of water to the boiler is connected into the feed water pipe instead of into the steam pipe, the desired differential between feed water pressure and boiler pressure being obtained and maintained by means of my improved static column applied to augment the boiler pressure, and control of the quantity of water delivered to the boiler being effected by throttling the water pipe by means of the control valve—the combined steam pressure and mercury column head tending to open the control valve and the feed water pressure tending to close said valve.

With this construction it is obvious that, as the steam pressure falls, or the feed water pressure rises, the excess of the water pressure will flex the diaphragm in a direction tending to close the control valve, thus throttling the feed water pipe and reducing the pressure of water admitted to the boiler. On the other hand when the steam pressure rises or the feed water pressure falls, the excess steam pressure will flex the diaphragm in a direction to open the control valve in the feed water pipe, thus increasing the water pressure and maintaining the de-

sired excess of feed water pressure above steam pressure.

In this application of my improved static column, the direction of flow in the feed water pipe will be reversed from the direction of flow in Figs. 1 and 2, the relation being such that the diaphragm will be exposed to the feed water pressure after it has passed through said valve—that is, after instead of before it has been throttled, as is the case with the steam pressure in the application shown in Figs. 1 and 2.

Describing the application of my improved static column with reference to Fig. 8, A² designates the control valve, 8² the trunk which communicates therewith, 7² the diaphragm casing, 9² the diaphragm, 12² the movable valve member, 13² the valve stem, 14², 15² the upper and lower mercury pots, 16² the tube connecting said pots, 29 a pipe which connects the lower mercury pot with the compartment 11² of the diaphragm casing and 30 a pipe connecting the upper mercury pot with the source of steam supply.

Water to replace leakage from the diaphragm casing and pipe 29, or lower pot 15² is adapted to be supplied by means of a valve controlled pipe connection 31, which connects the high pressure side of the feed water pipe or other source of supply of water under pressure, with the pipe 29.

As showing a slightly different form and application of my improved mercury column, I have in Fig. 9 of the drawings shown said column as applied in use to a regulator for producing a constant pressure reduction.

In this embodiment, one side of the diaphragm is subjected to the fluid pressure in the discharge or low pressure side of the valve, the opposite side of said diaphragm being subjected to the pressure of a mercury column corresponding in height to a desired constant low pressure on the discharge side of said control valve.

As thus applied, the mercury column consists of upper and lower mercury pots connected by a tube which communicates with said pots, respectively, adjacent to the designed minimum mercury levels therein, or adjacent to their lower ends, the lower pot being connected with the compartment of the diaphragm casing remote from the control valve by a pipe which communicates with said pot above the designed maximum mercury level therein, said pipe, the compartment of the diaphragm casing with which it communicates, and the lower mercury pot above the mercury level therein being filled with liquid through which the pressure of the mercury column is transmitted to the diaphragm.

In this application also, the top of the upper mercury pot usually is open and is adapted to be closed by a removable cover

which is provided with a vent opening for maintaining atmospheric pressure in said pot.

Describing this application of my improved mercury column with particular reference to Fig. 9 of the drawings, A³ designates the control valve, 1³ the valve casing, 2³ the admission or variable high pressure side of the casing, 3³ the discharge or constant low pressure side of the valve casing, 7³ the diaphragm casing, 8³ the trunk which connects said diaphragm casing with the discharge or low pressure side of the valve casing, 9³ the diaphragm which divides the diaphragm casing into separate compartments 10³ and 11³, 12³ the movable valve member, 13³ the valve stem connecting the said movable valve member with the diaphragm 9³, 14³ and 15³ the upper and lower mercury pots, 16³ the tube which connects said pots, and 32 the pipe which connects the lower mercury pot above the designed maximum mercury level therein with the compartment 11³ of the diaphragm casing.

As stated, also, the top of the upper mercury pot is preferably open and is adapted to be closed by a removable cover 33 to exclude dirt, said cover being provided with a vent opening 34 adapted to maintain atmospheric pressure in said mercury pot under all operating conditions.

As explained in connection with the device illustrating other applications of my improved mercury column, each mercury pot 14³ and 15³ is proportioned to hold somewhat more than all of the mercury in the apparatus, thus effectually preventing mercury from passing from the mercury pot into the pipe which connects it with the diaphragm casing.

With the described construction, it is obvious that the pressure at the discharge or low pressure side of the control valve casing will tend to flex the diaphragm 9³ in a direction to close the valve A³, while the pressure on the said diaphragm due to the pressure of the static mercury column will tend to flex said diaphragm in a direction to open the valve.

Thus, when there is no pressure above atmosphere in the valve casing, the pressure of the mercury column will maintain the valve fully open, in which position it will remain until a fluid pressure is produced in the discharge or low pressure side of the valve casing in excess of the pressure of the mercury column, whereupon the diaphragm 9³ will be flexed to close the valve, such closing movement continuing until the valve is throttled to such an extent that the pressure at the discharge side of the valve will be equal to the pressure of the static column of mercury. Any increase at the fluid discharge or low pressure side of the valve will operate to flex the diaphragm slightly to re-

duce the fluid flow until a balance of the pressures on opposite sides of the diaphragm is reached. On the other hand any decrease in the fluid pressure at the discharge or low pressure side of the valve casing will permit flexure of the diaphragm under the pressure of the mercury column to open the valve slightly, thus increasing the fluid flow through the valve and increasing the pressure at the discharge or low pressure side of the valve casing until, as before, a balance is reached on opposite sides of the diaphragm—thus, at all times, maintaining a substantially constant low pressure at the discharge side of the valve casing, in the manner desired.

Water to replace leakage in the compartment 11³ of the diaphragm casing, the pipe 32, the lower mercury pot 15³ and their connections, can be supplied by a pipe 35 adapted for connecting the pipe 32 with a source of supply of water under pressure, not shown, greater than that of the mercury column.

Also, to provide for lowering the heights of the static column to reduce the pressure in the compartment 11³ of the diaphragm casing to correspond to a desired constant low pressure at the discharge side of the control valve casing—should conditions require—said static column preferably comprises means for discharging water from said static column. As shown, said means consists of a valve—preferably a needle valve—indicated at 36, connected into the pipe 32 and adapted to discharge water therefrom, thereby lowering the effective height of the static column, in the manner desired.

If desired, however, my invention contemplates the use of a closed upper mercury pot for the mercury column shown in Fig. 9, the mercury only partially filling said pot and the space above the mercury being filled with air or other elastic fluid under pressure, which will augment the pressure of mercury column and will permit the use of a relatively small quantity of mercury. Said pot will be proportioned to provide a space above the mercury of such large size that variations in the pressure of the fluid contained therein, due to changes of the mercury level, in operation, will be negligible.

This modification is shown in Fig. 10 of the drawings, in which 14⁴ designates the upper mercury pot and 16⁴ the tube which connects it with the lower mercury pot, not shown, the mercury level and 37 the space above the mercury adapted to contain air or other elastic fluid under pressure. The pot 14⁴ is proportioned to provide a space 37 of such large size that variations in the pressure of the elastic fluid contained therein due to contemplated changes of the mercury level in operation, will be negligible.

To provide for charging said pot with

fluid under pressure, it is equipped with a valve controlled fitting 38 adapted for making supply connections thereto.

The pressure regulating means shown in Figs. 8 and 9 may readily be constructed to automatically vary the effective height of the mercury column to compensate for varying resistances to the current flow, by substituting for the tubes 16², 16³ of the mercury columns shown in said Figs. 8 and 9, respectively, tubes having enlarged lower portions 23 provided with small passageways 23 as shown in Figs. 2 to 7, inclusive, and heretofore described.

15 In all pressure regulating apparatus which embody my improved static column, means are preferably provided for retarding flexure of the diaphragm and opening or closing of the control valve under sudden variations 20 of the fluid pressure in either compartment of the diaphragm casing—or stated differently, for restoring the balance of pressure in the compartments of the diaphragm casing gradually under such sudden variation 25 of fluid pressure.

In the apparatus shown in Fig. 1, this is effected by throttling the pipe 17; in Fig. 2, by throttling the pipe 19'; in Fig. 8 by throttling the pipe 29; and in Fig. 9 by throttling 30 the pipe 32.

Convenient means for thus throttling said pipes consists of valves—preferably needle valves—connected into said pipes 17, 19', 29 and 32, respectively, said valves being designated 35 in all of the different views.

My invention, however, contemplates any other means for throttling said pipes.

If for any reason desired, also, my invention contemplates throttling both of the pipes 40 17 and 19, Fig. 1; 17' and 19', Fig. 2; and the pipes 29 and 30, Fig. 3.

A particular advantage in throttling the pipes 19, 19' and 30 in said Figs. 1, 2 and 3, respectively, is that, in case any part of the 45 mercury column beyond the lower mercury pot should become ruptured or blow out, fluid under pressure would be delivered thereto in such small quantities that it would not blow the mercury out of the apparatus, 50 as might happen if said pipes were not throttled and fluid under pressure in large volume were delivered to the ruptured apparatus.

While I have described my invention with 55 particular reference to a static mercury column, I do not desire to limit myself to the use of mercury and I therefore desire it to be understood that reference to a mercury column in the specification, merely exemplifies a static column in which any suitable liquid is employed to produce a desired differential stress.

Also, while I have described the invention with reference to a flexible diaphragm,

I do not desire to limit myself to the use of 65 a diaphragm but to employ any other equivalent motive means for operating the regulating valve where the nature of the fluid used or mechanical condition may render the use of such other motive means desirable.

What I claim is:—

1. In a fluid pressure regulator of the type specified, the combination of a source of supply of fluid under pressure, a pressure generator, a pipe line which connects said source of fluid supply with said pressure generator, a control valve connected into said pipe line comprising a movable control member, motive means comprising a movable member exposed on one side to the pressure from said source of fluid supply and on its opposite side to the pressure of said pressure generator less the pressure of a static liquid column comprising a mercury leg 85 comprising closed upper and lower pots, and a tube which connects said pots and which communicates with said pots, respectively, adjacent to their lower ends, each of said pots being proportioned to hold all of the 90 mercury in the apparatus, and a water leg applied directly to said movable member and which communicates with the upper pot of the mercury column above the designed mercury level therein, and a pipe which 95 connects the lower mercury pot above the designed mercury level therein with the pressure generator, and means which connects said movable motive member with the movable valve control member.

2. In a fluid pressure regulator of the type specified, the combination of a source of supply of fluid under pressure, a pressure generator, a pipe line which connects said source of fluid supply with said pressure generator, a control valve connected into said pipe line comprising a movable control member, a diaphragm casing, a diaphragm which divides said casing into separate compartments, a trunk which connects a compartment of said diaphragm casing with a chamber of the valve casing, and a static column applied to the chamber of said diaphragm casing other than that which 110 communicates with the control valve casing, comprising a water leg which communicates directly with said diaphragm casing, and a mercury leg comprising closed upper and lower pots, and a tube which connects said 115 pots, and which communicates therewith, respectively, adjacent to their lower ends, each of said pots being proportioned to hold all of the mercury in the apparatus, and the water leg of the static column communicating with the upper pot above the designed mercury level therein, and a pipe which connects the lower pot with the discharge line 120 of the fluid pressure generator above the de-

signed mercury level in said lower pot, and means which connects the diaphragm with the movable valve control member.

3. A fluid pressure regulator as specified
5 in claim 1, which comprises means for throttling a pipe forming part of the connection by which pressure from the pressure generator is transmitted to the motive member, to retard movement of said motive member
10 due to changes of pressure.

4. A liquid column for producing a static stress, comprising upper and lower pots, a tube which connects said pots, each of said pots being proportioned to hold all of the liquid forming the static column, and a pipe adapted for connecting one of said pots with a closed expansible chamber.

5. A liquid column for producing a static stress as specified in claim 4, in which the upper pot has pipe connection with the closed expandible chamber.

6. A liquid column for producing a static stress as specified in claim 4, in which pipes communicate with both the upper and lower pots adapted for connecting said pots, respectively, with a closed expansible chamber and with a source of supply of fluid under pressure.

7. A liquid column for producing a static
30 stress as specified in claim 4, in which pipes
communicate with both the upper and lower
pots adapted for connecting said pots, re-
spectively, with a closed expansible cham-
ber and with a source of supply of fluid
35 under pressure the specific gravity of which
is less than that of the liquid forming the
static column.

8. A liquid column for producing a static stress, comprising upper and lower pots, a tube which connects said pots, each of said pots being proportioned to hold all of the liquid forming the static column, a pipe adapted for connecting one of said pots with a closed expansible chamber, and means for varying the effective height of the static column.

50 9. A liquid column for producing a static stress, comprising upper and lower pots, a tube which connects said pots, each of said pots being proportioned to hold all of the liquid forming the static column, a pipe adapted for connecting one of said pots with a closed expansible chamber, and means for automatically varying the effective height of the static column.

60. 10. A liquid column for producing a static stress, comprising upper and lower pots, a tube which connects said pots, each of said pots being proportioned to hold all of the liquid forming the static column, and a pipe adapted for connecting one of said pots with a closed expansible chamber, the tube connecting the upper and lower pots comprising a lower portion provided with passageways of such small size that liquid of less specific

gravity than that which forms the static column proper will not rise through said passageways when they contain liquid forming said static column, the aggregate cross-sectional area of said passageways being less than that of the upper pot and the lower end of the liquid forming said static column terminating within and between the ends of said passageways, whereby movement of the liquid forming the static column proper will be in the same direction throughout its length and differential variations in the levels of opposite ends of said static column will be produced, thereby automatically varying the effective height thereof. 70 75 80

11. A liquid column for producing a static stress as specified in claim 10, in which the means for varying the effective height of the static column also comprises means adapted for discharging water from the pipe connecting a pot of said static column with said expansible chamber and for forcing liquid into the same. 85

12. A liquid column for producing a static stress, comprising upper and lower pots, a tube which connects said pots, each of said pots being proportioned to hold all of the liquid forming the static column, pipes which communicate with both the upper and lower pots adapted for connecting said pots, respectively, with a closed expansible chamber and with a source of supply of fluid under pressure, the tube connecting the upper and lower pots comprising a lower portion provided with passageways of such small size that liquid of less specific gravity than that which forms the static column will not rise through said passageways when they contain liquid forming said static column, the aggregate cross-sectional area of said passageways being less than that of the upper pot and the lower end of the liquid forming said static column terminating within and between the ends of said passageways, whereby movement of the liquid forming the static column will be 90 95 100 105 110

forming the static column proper will be in the same direction throughout its length and differential variations in the levels of opposite ends of said static column will be produced, thereby automatically varying the effective height thereof, and a by-pass which connects the pipes which communicate, respectively, with the upper and lower pots of the mercury column, equipped with a discharge valve to atmosphere and with a valve adapted for admitting fluid under pressure directly from the pipe which communicates with the lower pot to the pipe which communicates with the upper pot. 115 120

13. A liquid column for producing a static stress comprising upper and lower pots, a tube which connects said pots and which communicates with said pots, respectively, adjacent to their lower ends, each of said pots being proportioned to hold all of the

liquid forming the static column, and a pipe adapted for connecting one of said pots above the designed maximum level therein of the liquid forming said static column with a closed expandible chamber.

14. A liquid column for producing a static stress as specified in claim 13, in which the upper pot is adapted to be connected with the expandible chamber.

10 15. A liquid column for producing a static stress as specified in claim 13, in which pipes communicate with both the upper and lower pots above the designed maximum levels therein of the liquid forming the static

15 column proper, adapted for connecting said pots, respectively, with a closed expandible chamber and with a source of fluid under pressure.

16. A liquid column for producing a static 20 stress as specified in claim 13, in which pipes communicate with both the upper and lower pots above the designed maximum levels therein of the liquid forming the static column, adapted for connecting said pots,

respectively, with a closed expandible chamber and with a source of supply of fluid under pressure the specific gravity of which is less than that of the liquid forming the static liquid column.

17. A liquid column for producing a static 30 stress as specified in claim 13, which comprises means for throttling the pipe which connects said mercury pot and closed expandible chamber.

18. A liquid column for producing a static 35 stress as specified in claim 13, in which pipes communicate with both the upper and lower pots above the designed maximum levels therein of the liquid forming the static column proper, adapted for connecting said 40 pots, respectively, with a closed expandible chamber and with a source of supply of fluid under pressure, and means for throttling one of said pipes.

In witness that I claim the foregoing as 45 my invention, I affix my signature this 2nd day of February, 1925.

ELMER T. McCARTHY.
